RUFUS McC. BEANFIELD, OF SAN FRANCISCO, CALIFORNIA.

APPARATUS FOR DISTRIBUTING CONCRETE.

1,094,111.

Specification of Letters Patent. Patented Apr. 21, 1914.

Application filed April 21, 1913. Serial No. 762,522.

To all whom it may concern:

Be it known that I, RUFUS McC. BEANFIELD, a citizen of the United States, residing in the city and county of San Francisco and State of California, have invented certain new and useful Improvements in Apparatus for Distributing Concrete, of which the following is a specification.

My invention relates to that class of concrete distributing apparatus in which a distributing system of troughs, pipes or other conveyers are used in connection with an elevator tower.

The object of my invention is to provide an apparatus of this class, simple, practical and effective in construction, and which will permit indefinite range of distribution.

To this end my invention consists in the novel apparatus which I shall now fully describe by reference to the accompanying drawings, in which—

Figure 1 is a side elevation of my concrete distributing apparatus. Fig. 2 is a fragmentary horizontal section on the line $\alpha-\alpha$ of Fig. 1. Fig. 3 is a fragmentary side elevation of one of the conveying troughs. Fig. 4 is a plan view of the same. Fig. 5 is an elevation, enlarged, of the revoluble head-hopper of the second trough. Fig. 6 is a section on line $y-y$ of Fig. 5. Fig. 7 is a side elevation, enlarged, of a third trough. Fig. 8 is a plan view of the same. Fig. 9 is a vertical section, enlarged, of the fixed receiving box on the tower, showing its directing means, and its connections, with their controlling gates.

Referring, first, to Fig. 1, 1 is a tower of any suitable construction, rising from a base 2, on which is indicated a mixer 3. In the tower is the elevator 4, operated by a cable 5, driven by a hoisting mechanism at 6. 7 are the guy-cables of the tower. These are in sufficient number in series about the tower, four being shown in Fig. 2. In Fig. 1 I show but one of these guy-cables produced to its foot at 8, though it is to be understood that the others are likewise arranged.

Secured to the tower near its upper end is the receiving box 9 into which the elevator 4 delivers the concrete in customary manner. This box 9 has two discharge spouts 10, one near the bottom of each side, and each spout is fitted with a controlling gate 11, which is operated by a handle 12, as seen in Fig. 9.

Secured to the box on each side around the spouts 10 is a short-chute 13, each of said chutes having, as shown in Fig. 2, two divergent branches 14, under the outer end of each of which is a short head-trough 15, supported from the tower by links 15', as seen in Fig. 1. One of these head-troughs leads in the direction of and underlies one of the guy-cables 7, and the other leads similarly to an adjacent guy-cable; thus providing, as shown clearly in Fig. 2, four such head-troughs, one for each guy-cable.

Within the box 9, as shown in Fig. 9, and in dotted lines in Fig. 1, is removably fitted a directing plate 9'. In the position shown this plate delivers the concrete to the spout 10 on the right; but when the plate is changed to the opposite angle, it delivers the concrete to the spout on the left. In each short chute 13 where its branches 14 lead off, is placed a controlling plate 16, as seen in Fig. 2. This plate may slide into place or it may be hinged, the latter being indicated. Its position is such that it can close either branch 14 and open the other.

17, in Fig. 1, is the main trough. This is composed of a plurality of freely overlapping sections in end alignment, as shown in Figs. 3 and 4. The sections are flexibly connected or articulated in suitable manner. A good construction is that shown in said Figs. 3 and 4, namely rods 18 seated in the curled edges 19 of the trough sections, the meeting ends of said rods being hooked together as shown at 20. The main trough 17 is suspended from and carried by any one of the guy-cables 7 by suitable hangers, such, for example, as the bails 21. The upper end of the main trough 17 lies under any one of the head-troughs 15 in position to receive the concrete therefrom.

Suspended from the guy-cable 7 from which the main-trough 17 is suspended is a hanger rod 22, said rod being hung from the cable by its hook 23. Upon this hanger 22 is carried a hopper 24, said hopper being revoluble on the hanger as an axis by means of the base bracket 25, as seen in Fig. 5. Upon the hanger 22 is mounted and adapted to be vertically adjusted by means of a collar 26 having a set screw 27, a spider 28, the arms of which, as shown at 29 in Figs. 5 and 6, are hooked into the terminals of the main-trough edge-rods 18, whereby the delivery

end of said main-trough is adjustably carried and held in position to discharge the concrete into the hopper 24. The other ends of the spider-arms are secured to a shield 30, the lower end of which fits freely into the hopper, and its upper end is carried by an adjustable collar 31 on the hanger-rod 22.

The hopper 24 is fitted with a discharge spout 32. Under this spout lies the upper end of the second trough 33, as shown in Fig. 1. This trough is similar in construction to the main-trough, that is composed of articulated sections. It is suspended by bails 34 from a cable 35 the upper end of which is secured to the guy-cable 7, and the lower end of which is connected to a fixed point by a block and tackle at 36, as seen in Fig. 1. This second trough may be the terminal of the distributing apparatus or more troughs may be added. For example, I show in Figs. 1, 7 and 8 provision for a third trough 37. This trough has an enlarged head 38 and is suspended by bails 39 from a beam 40. The upper end of this beam has a bracket 41 which is revolvably carried on a hanger 42 suspended from the cable 35. A bail 43 flexibly connects the lower end of the second trough 33 with the hanger 42, said end being disposed properly to deliver the concrete into the enlarged head 38 of the third trough 37. The lower end of the beam 40 is supported on a foot block 44 to which it is secured by a handled bracket 45.

The operation of the apparatus is as follows:—The concrete is carried up by the elevator 4 and dumped into the box 9. By the plate 9' in said box, the concrete is directed into the spout 10 to the right. By the plate 16 in the chute 13 of this spout, it is directed into that head trough 15 with which the main trough 17 is in communication. The concrete passes down through the main trough 17 and is delivered into the hopper 24 which delivers it to the second trough 33. Assuming the second trough to be the terminal of the system, it will be seen that by releasing the lower end of the cable 35 from which it hangs and carrying said cable around and securing it in successively fresh positions in its circle of movement, the second trough 33 turns with its revolute hopper 24 through a complete circle and will deliver the concrete throughout its range of movement. The area thus served can be enlarged by removing some of the terminal sections of the main trough 17, adding to the sections of the second trough 33, slipping the connections of the cable 35 and the hopper hanger rod 22 farther up on the guy-cable 7, and lengthening the cable 35 by its block and tackle 36. When the area within range of the apparatus as thus described has been served, the main trough 17 is unslung from the guy-cable 7 which had previously supported it, and said trough is moved bodily to

a new relation with another head trough 15 of the box 9 and is then suspended from another of the guy-cables 7. In this readjustment to a new position, the second trough 33 accompanies it, the cable 35 of said trough having been freed. When the parts are in their new position, the various controls of the box 9 are properly rearranged for delivering the concrete to the main trough, and the operation proceeds until the distribution to the new area has been completed, whereupon a third rearrangement is had, and so on throughout the whole circle. For a further range of action, the third trough 37 may be used, said trough having an operation relatively to the second trough 33 similar to that which the latter has to the main trough 17, and, moreover, said third trough may be relatively short and light adapting it for easy manipulation through its handle 45.

In this general type of apparatus for distributing concrete I am aware that it is not new to provide for a circular range of distributive area and to augment this range by a series of secondary areas, said result being effected by connected, separately revoluble conveying systems. It is customary, however, to support these systems directly from the tower, by booms and overslung cables. But there is a practical limit to such support, both in the strength of the tower and in the leverage, weight and length of the pipes. In contradistinction to this customary method, the essential feature of my invention lies in the suspension of my distributing system from a catenary support. This gives many advantages, such, for example, as the relief of the tower, the indefinite extension of the system, the adjustment of the system to reach any given distributive area, and numerous others which will readily suggest themselves to workers in this art, and of which I may state but one more but very decided benefit, namely, that arising from the remixing or further mixing of the material owing to the flow or passage of said material in the catenary curve of the trough so suspended, permitting a minimum amount of mixing in the preliminary mixer machine.

Though I have herein shown the catenary support for the main trough as the guy-cable of the tower, I do not confine myself to this. Such support may be any suitable catenary, whether the tower guy or another cable specifically provided.

I claim:—

1. In an apparatus for distributing concrete, the combination of an elevator tower; a main trough in relation to the tower to receive the concrete from the delivery devices thereof; a catenary support from which said main trough is suspended; a hopper revolvably suspended from said catenary support in position to receive the concrete from the main trough; a second trough in commun- 120

cation with the hopper; and a second catenary support from which the second trough is suspended.

2. In an apparatus for distributing concrete, the combination of an elevator tower; a main trough in relation to the tower to receive the concrete from the delivery devices thereof; a catenary support from which said main trough is suspended; a hopper revolvably suspended from said catenary support in position to receive the concrete from the main trough; a second trough in communication with the hopper; and a second catenary support from which the second trough is suspended, said second catenary support having one of its ends connected with the first catenary support.

3. In an apparatus for distributing concrete, the combination of an elevator tower; a main trough in relation to the tower to receive the concrete from the delivery devices thereof; a catenary support from which said main trough is suspended; a hopper revolvably suspended from and adjustable lengthwise upon said catenary support in position to receive the concrete from the main trough; a second trough in communication with the hopper; and a second catenary support from which the second trough is suspended, said second catenary support having one of its ends connected with the first catenary support and its other end extensibly connected with a fixed point below.

4. In an apparatus for distributing concrete, the combination of an elevator tower; a main trough in relation to the tower to receive the concrete from the delivery devices thereof; a catenary support from which the main trough is suspended; a hopper disposed in relation to the delivery end of the main trough to receive the concrete therefrom; a hanger rod suspended from said catenary support, said hanger rod revolvably supporting said hopper; a second trough in communication with the hopper; and a second catenary support from which the second trough is suspended.

5. In an apparatus for distributing concrete, the combination of an elevator tower; a main trough in relation to the tower to receive the concrete from the delivery devices thereof; a catenary support from which the main trough is suspended; a hopper disposed in relation to the delivery end of the main trough to receive the concrete therefrom; a hanger rod suspended from said catenary support, said hanger rod revolvably supporting said hopper; a shield freely fitting in the hopper opposite the end of the main trough; a spider carried by the hanger rod and connecting the main trough and shield; a second trough in communication with the hopper; and a second catenary support from which the second trough is suspended.

6. In an apparatus for distributing concrete, the combination of an elevator tower; a main trough in relation to the tower to receive the concrete from the delivery devices thereof; a catenary support from which the main trough is suspended; a hopper disposed in relation to the delivery end of the main trough to receive the concrete therefrom; a hanger rod suspended from said catenary support, said hanger rod revolvably supporting said hopper; a shield freely fitting in the hopper opposite the end of the main trough; a spider carried by the hanger rod and connecting the main trough and shield; said spider being vertically adjustable upon the rod; a second trough in communication with the hopper; and a second catenary support from which the second trough is suspended.

7. In an apparatus for distributing concrete, the combination of an elevator tower; a main trough in relation to the tower to receive the concrete from the delivery devices thereof; a catenary support from which said main trough is suspended; a hopper revolvably suspended from said catenary support in position to receive the concrete from the main trough; a second trough in communication with the hopper; a second catenary support from which the second trough is suspended, said second catenary support being connected at its upper end with the first catenary support; a third trough arranged to receive the concrete from the second trough; a support from which the third trough is suspended, and means for revolvably suspending the upper end of said third trough support from the catenary support of the second trough.

8. In an apparatus for distributing concrete, the combination of an elevator tower; a plurality of guy-cables for said tower; a main distributing trough suspended from and lengthwise of any one of said guy cables, said trough being disposed to receive at its upper end the concrete from the delivery devices of the tower; a hopper revolvably suspended from said guy-cable and disposed to receive the concrete from the foot of the main trough; a second trough in communication with said hopper; a second cable attached at its upper end to the guy-cable and attached at its lower end to a fixed point below; and means for suspending said second trough from said second cable.

9. In an apparatus for distributing concrete, the combination of an elevator tower; a longitudinally flexible main-trough in relation to the tower to receive the concrete from the delivery devices thereof; a catenary support from which said main-trough is suspended; a hopper revolvably suspended from said catenary support in position to receive the concrete from the main-trough; a second longitudinally flexible

trough in communication with the hopper; and a second catenary support from which the second trough is suspended, said second catenary support having one of its ends connected with the first catenary support.

10. In an apparatus for distributing concrete, the combination of an elevator tower; a series of catenary cables secured at their upper ends to the tower and at their lower ends to fixed points below; a distributing trough; means for removably suspending

said trough from and lengthwise of any one of said cables; and means in the tower for feeding the concrete to said trough when suspended from any of said cables.

15 In testimony whereof I have signed my name to this specification in the presence of two subscribing witnesses.

RUFUS McC. BEANFIELD.
